UNITED STATES PATENT OFFICE

GEORGE W. BEADLE, OF NEW YORK, N. Y.; HAROLD I. BEADLE, ADMINISTRATOR OF SAID GEORGE W. BEADLE, DECEASED, ASSIGNOR TO THE CELLA-COTE COMPANY, INC., A CORPORATION OF NEW YORK

METHOD OF AND APPARATUS FOR COATING ARTICLES

Application filed May 27, 1927. Serial No. 194,609.

This invention relates to the covering of articles with a protective coating, and has reference more particularly to the application to the article of a coating material in liquid form and its subsequent treatment while on the article to cause it to harden and set, as set forth in an application filed by me August 12, 1925, Serial No. 49,680.

The invention is concerned especially with the coating of perishable articles, viz., fruits, vegetables, and the like, such for instance as eggs, etc., to preserve the same from deterioration or decay, and thus prolong their edible periods, but the invention is applicable as well as will be apparent from the description to follow, to the coating of other commodities and articles to protect them and facilitate their shipment and handling, and to preserve them in sanitary condition.

The coating material which it is preferred to employ in carrying out the invention is a hydrated cellulose solution such as xanthate cellulose, which in accordance with the invention, is applied to the articles in an improved manner and by means of an apparatus of improved form so as to completely cover the article, and the coating thereafter subjected to treatment in suitable treating solutions which will have the effect of coagulating and purifying the cellulose coating and cause it to become transparent, which on drying will shrink and embrace the article under initial tension.

The invention therefore consists of the improved coating apparatus, and the improved method involved in the operation of said apparatus; and in the specification to follow the invention will be described in detail and the novel features thereof will be set forth in the appended claims.

In the accompanying drawings:

Fig. 1 is a side elevation of the improved apparatus, certain of the tanks for the treating solutions being omitted.

Fig. 2 is a vertical longitudinal sectional elevation of the same.

Fig. 3 is a sectional view on an enlarged scale of the forward end of the tank of the first treating solution, showing in elevation a portion of the conveyor chain in the act of

discharging the coated article into the tank for treatment.

Fig. 4 is a view in side elevation on an enlarged scale of the rear end of one of the conveyor chains, showing the driving support for said chain and the device for controlling the position of the articles in their passage around the driving support.

Fig. 5 is a plan view broken away and showing at the top of the figure the upper stretch of one set of conveyor chains, and at the bottom of the figure the lower stretch of an adjacent set of conveyor chains.

Fig. 6 is a vertical sectional elevation on an enlarged scale on the line 6—6 of Fig. 2 as viewed in the direction of the arrows on said line.

Fig. 6^a is a fragmentary sectional view on the line 6^a—6^a of Fig. 2.

Fig. 7 is a vertical sectional elevation on the line 7—7 of Fig. 2.

Fig. 8 is a perspective view of one of the article-holding baskets, the same being detached from its carrying chains.

Fig. 9 is an end elevation of the same, showing in full lines receiving position of the basket, and in dotted lines its discharging position.

Figs. 10 and 11 are diagrammatic views showing the different positions in which the articles are supported to receive the coating material and the air blast.

Fig. 12 is a view in the nature of a diagram of the entire apparatus showing how the articles after receiving the coating material are subjected successively to the treating solutions, the water bath, and are finally dried.

Fig. 13 is a plan view of the same.

Fig. 14 is a side elevation of mechanism for feeding the articles automatically to the conveyor chains and at the same time applying a preliminary covering of the coating material.

Fig. 15 is a similar view of said mechanism with the parts in a different position.

Fig. 16 is a top plan view of the same.

Fig. 17 is an elevation of the receiving end of the conveyor chains showing the same in

operative relation to the article feeding mechanism of Figs. 14, 15 and 16.

Referring to the drawings:

As best shown in Figs. 1, 2, 12 and 13, the improved machine comprises an endless conveyor 1 to which the articles A to be coated are fed and by which the articles are carried beneath nozzles 2 and 2^a for furnishing the cellulosic coating material; a tank 3 containing a neutral salt solution such as ammonium sulfate into the forward end of which the coated articles are discharged by the conveyor 1 onto a conveyor 4 in the tank, which latter conveyor carries the articles rearwardly in the tank; a second tank 5 containing an acid solution such as sulfuric acid, into the forward end of which the articles are delivered by the conveyor onto a conveyor 6 in the tank 5 which carries the articles rearwardly in said tank; a third tank 7 containing washing water into the forward end of which the articles are delivered by the conveyor 6 onto a conveyor 8 in the tank 7 by which the articles are carried rearwardly in said tank; a conveyor 9 which receives the articles from the conveyor 8 and which carries them rearwardly beneath a nozzle 10 for applying a softening solution to prevent the coating when dried from becoming too brittle; and a drier 11 into which the articles are delivered by the conveyor 9 for their final drying.

The articles subjected to the action of this mechanism are first completely covered with the coating material flowing downwardly from the nozzles 2 and 2^a, the said articles after receiving the flow of material from the first nozzle being changed in position and presented to the second nozzle in its changed position so that the material will flow on such portions of the article, as may have been left uncovered by the material from the first nozzle, and the article will be completely covered by the coating material. The coated articles are now carried by the conveyor rearwardly on its upper stretch and then returned forwardly on its lower stretch, the comparatively long path of travel of the articles giving time for the coating material to drain from the articles and to distribute itself evenly and uniformly over the articles, which action is facilitated by reversing the position of the articles as they reach a point about midway of their return travel, such reversal of the articles being effected by turning the same a half revolution on the conveyor. At the end of their travel the articles with the coating material evenly and uniformly distributed thereon are passed successively through the ammonium sulfate treating solution and the sulfuric acid treating solution respectively in the tanks 3 and 5, the effect of which solutions will be to coagulate and purify the coating and render the same self-holding and transparent. The articles with the coagulated and purified coating thereon

are washed in the water bath in tank 7, which washing action will remove all traces of the treating solutions and in this condition the articles are covered with a softening material issuing from the nozzle 10 and are then finally dried in the drier 11.

As a result of these operations as carried out in the apparatus above described, the uncoated articles fed into the machine are so acted on by the several automatically acting cooperating units that said articles issue from the machine each completely enveloped in a homogeneous transparent non-adherent coating embracing the article under initial tension.

The operative parts of the apparatus are mounted in and sustained by a suitable frame consisting of uprights 13 extending upwardly from the opposite sides of the tank 3, cross bars 14 connecting the opposing uprights, and longitudinal bars 15 connecting said uprights and extending at their forward ends beyond the forward end of the tank and forming a front frame extension 15^a.

The conveyor 1 is mounted in this framework and is made up of a number, in the present instance six, conveying units to give the machine greater capacity, each of which units is identical in form and construction and all of which are operated from a common source of power, so that at one time a great number of articles can be handled and subjected at the same time to the coating operation; but it will be understood that a greater or less number of units may be provided without departing from the limits of the invention the advantages and purposes of which could be realized by the employment of but a single conveyor unit.

As best shown in Figs. 5, 6, 8, 9 and 13, each conveyor unit comprises two endless chains 16 traveling side by side in spaced relations and mounted and driven in the manner presently to be described, and article holders in the form of baskets or cages 17 of the construction shown in Figs. 8 and 9, which baskets are loosely suspended at intervals between the links of the opposing chains, so that while said baskets will be pulled along by the travel of the chains they may be caused in such travel to assume different angular positions relative to the chains to the end that the coating material will be caused to completely cover the articles held in the baskets, and will be evenly and uniformly distributed thereon.

As shown in Fig. 8, each basket comprises two end inverted U frames 18 formed with upper arms 18^a and angularly related lower arms 18^b, which end frames are connected together by upper opposing side bars 19 and lower opposing side bars 20, which bars are provided with article-supporting pins 21 and 22 projecting at intervals respectively therefrom and have their extremities rounded as

shown, the spacing of the bars 19 being such that the articles will be received between the bars when the basket is in its upright receiving position, and in such position the article will rest on the lower pins 22 as shown in Fig. 9. At their upper ends the end frames 18 of the baskets have pivoting studs 17^a projecting outwardly therefrom, which studs are journaled in the links 16^a of the opposing chains, whereby the baskets are gravitatingly suspended from the chains and can tilt and rock relatively thereto and assume the different angular positions referred to, and can also be reversed in position as shown by dotted lines in Fig. 9 when the articles are to be discharged from the baskets as will be described later on.

At the forward end of the machine the chains of the several units pass over the sprocket wheels 23 on a shaft 24 mounted in bearings on the frame extension 15^a, and at the rear the chains pass around sprocket wheels 25 on a shaft 26 journaled in bearings in the upper ends of the rear frame uprights 13. The shaft 26 has fixed to it a driving sprocket wheel 27 driven from a sprocket chain 28 receiving its motion from a sprocket wheel 29 from a main driving shaft 30 as shown in Fig. 13, by which means the chains of the several units will be driven in unison to cause their upper stretches to travel to the rear as indicated by the dotted arrow in Fig. 2.

A short distance in rear of the sprocket wheels 23, the chains pass beneath idler sprocket wheels 31 on a shaft 32 mounted in bearings on the frame extension 15^a, and from the undersides of the idler sprockets 31 the chains pass upwardly and over idler sprockets 33 loosely mounted on a shaft 34 journaled in bearings on the machine frame.

At a point adjacent the forward end of the tank 3, the chains pass under and around idler sprocket wheels 35 on a shaft 36 mounted in bearings 37 on the machine frame (see Figs. 2 and 6), and from these sprocket wheels the chains pass upwardly and over idler sprocket wheels 38 fixed to a shaft 39 journaled in bearings supported by the frame extension 15^a. From the sprocket wheels 38 the chains pass downwardly and around the lower sides of idler sprocket wheels 40 on a shaft 41 mounted in bearings on the frame extension, whence the chains pass upwardly and around the front sprocket wheels 23 before alluded to.

The material supplying nozzles 2 and 2^a hereinbefore referred to are positioned to distribute the coating material onto the articles held in the baskets as the latter are carried rearwardly by the chains from the front sprocket wheels as shown in Fig. 2, there being a set of these nozzles for each conveyor unit, which nozzles extend downwardly from a common horizontal distributing pipe 42

supplied with the coating material by a vertical pipe 43 connected at its upper end to said distributing pipe. The discharge ends of the nozzles are in vertical alignment with the path of travel of the articles in the baskets, so that as the articles pass beneath the nozzles in succession they will receive on their surfaces the coating material flowing downwardly from the nozzles.

It has been found that in covering articles which are of generally spherical form, for example fruits such as cantaloupes, oranges, grapefruit, and the like, the coating material if allowed to flow downwardly on the article will at the underside of the article tend to divide into two streams, which flowing from the surface of the article will leave an uncoated area on the underside. In order to prevent the occurrence of this uncovered area and insure that all parts of the surface will be covered by the material in its downward flow from the nozzles, I propose to change the position of the article after it receives the material from the first nozzle and present the article in a different position to the second nozzle, and in such position that the material flowing from the second nozzle will flow over the uncovered area left by the material from the first nozzle, so that the coating material supplied by the two nozzles will completely cover the entire surface of the article.

This change in position of the article is effected in the present instance by the construction and arrangement of parts shown in Fig. 2, where it will be seen that the article A is placed in its carrying basket as the latter travels upwardly at the forward side of the front sprocket wheels 23, the basket in this position of its travel being in an upright receiving position with the side bars 19 at the top so that the article can be placed between said bars and seated on the lower set of supporting pins 22. In this position of the basket the end frames of the same at their rear sides engage stop pins 44 projecting inwardly from the sides of the sprocket wheels, a number of said pins being provided and spaced apart on the wheels to correspond to the spacing of the baskets on the carrying chains. As the basket moves upwardly and rearwardly over the wheels, with the basket in engagement with its associated pins, it will in passing over the top side of the wheel turn through 90° and in this position will pass beneath the nozzle 2, thereby presenting the side of the article in position to receive the downwardly flowing material as shown in Fig. 2 and at the right in Fig. 10. On the continued movement of the chains rearwardly, carrying the basket with them, the associated pins will move out of engagement with the basket and the latter being no longer supported by said pins, will by gravity swing on its carrying chains to a pendant upright position, thereby moving the article in the bas-

ket back through 90° to its former position so as to present a different surface to the downward flow of the material from the nozzle 2^a as the basket passes beneath the nozzle 5 as shown in dotted lines in Fig. 2, and at the left in Fig. 10. The stream of coating material from the nozzle 2^a will, by reason of this change of position of the article, pass over and cover the area left uncovered by the first 10 stream, so that by the cooperative action of the two streams on the article presented at relatively different positions to the respective streams, the complete covering of the articles by the coating material is insured.

15 The surplus material leaving the articles as the latter pass beneath the nozzles, is caught in a receptacle or tank 45 suitably supported by the extension frame 15^a from which receptacle a pipe 46 leads downwardly 20 to a pump 47 by which the material is pumped back for use again by a pipe 48 connecting the discharge side of the pump with the supply pipe 43 before alluded to, it being understood that the supply of the material to the 25 receptacle 45 will be replenished from time to time to make up for the material used in coating the articles.

In the travel of the baskets from the nozzle 2^a to the idler sprockets 31 they pass beneath 30 air blast nozzles 49 and 50 (see Figs. 2 and 11), by which streams of air are directed onto the coated articles, the purpose of which is to remove the surplus material and aid in the distribution of the material on the articles; and in order that these air streams 35 may be caused to reach all portions of the coating, means are provided for changing the position of the articles after being acted on by the first stream so that a different surface of the coated article will be presented to the action of the second air stream. The air nozzles 49 and 50 extend downwardly from a horizontal air distributing pipe 49^a supplied with air under pressure from any 40 suitable source by a supply pipe 49^b, it being understood that there will be a set of 45 these nozzles for each conveyor element; and the ends of the nozzles of the several sets are arranged vertically over the lines of 50 travel of the baskets. As shown in Fig. 2 and at the right in Fig. 11, the baskets each pass beneath nozzle 49 in a vertical pendant position, but as the basket leaves nozzle 49 and approaches nozzle 50 it is rocked or 55 turned on its pivotal supports on the chains through approximately 90°, which rocking is effected by providing in the path of the baskets, a series of pairs of cam plates 51 fastened to a cross bar 52 supported on the frame 60 extension 15^a. The forward portions 51^a of the cam plates slope upwardly from their front ends, and the rear portions 51^b slope downwardly and rearwardly from the rear ends of the forward portions, and they are 65 so related to the paths of travel of the bas-

kets that the end frames of the baskets will as the baskets are drawn rearwardly by the chains in a vertical pendant position after leaving the air blast nozzle 49, ride up on the forward portions of the cam plates, and engaging the forward ends of the rear portions of the plates, the baskets will be turned on their pivotal supports on the chains through 70 90°, and the articles in their changed position will be presented beneath air blast nozzle 50 as shown in Fig. 2, and in Fig. 11 at the left. As the baskets in their continued rearward travel disengage the cam plates, they will 75 gravitate to an upright position and in this position will be carried upwardly to the idler 80 sprockets 33.

As the baskets are carried by the chains rearwardly over the sprocket wheels 33, the end frames of the baskets will engage and ride on longitudinally extending tracks 52 85 supported by vertical bars 53 fastened to the cross bars 14 before alluded to. These tracks are fixed to the sides of longitudinal rails 54 which are in turn fixed to the upper ends of the bars 53 as best shown in Fig. 6, the said 90 rails 54 giving support to the chains 16 in their travel. In the rearward movement of the baskets along the tracks 52, the lower arms 18^b of the end frames 18 at one side of the baskets will rest and travel on the tracks 95 as shown in Fig. 2 in which position of the baskets the articles therein are supported by the pins 21 and 22 at one side of the baskets, and the latter are maintained in this position throughout their travel on the upper stretch of the chains, and while passing over the rear sprockets 25, and until they reach a point about midway of their return travel on the lower stretch of the chains, at which point the baskets are automatically reversed in position and in such reversed position are carried along to the end of their return travel, at which point, the baskets are automatically turned with their bottom sides up to discharge the articles into the treating solution 100 110 in tank 5.

To effect these operations, the baskets as they are carried around the rear idler sprockets 25 are acted on by a series of upright pivotal arms 55 mounted on a horizontal transverse shaft, 56 journaled in bearings on the rear frame uprights 13, the said arms being acted on by weights 57 tending to urge the arms forwardly towards the baskets and in a position to engage and maintain engagement with the bars 19 of the baskets at one side. By such engagement the baskets are prevented from tipping or rocking on their carrying chains as they pass around the wheels 25 and are therefore held in the same position they occupied in their rearward travel on the tracks 52. As the baskets leave the lower side of the wheels and begin their return movement on the lower stretch of the chains, the lower arms 18^b of the end 115 120 125 130

frames of the baskets will pass onto longitudinally extending tracks 58 supported by the vertical bars 53 before alluded to, which tracks are fastened to the inner sides of longitudinal rails 59, which are in turn fastened to the inner sides of the bars 53 at their lower ends as shown in Fig. 6^a, the rails 59 thus serving to support the lower stretch of the chains similar to the support afforded the upper stretch by the rails 54. The baskets traveling in engagement with the tracks 58 as just described will be held in the same position relative to the chains they occupied in their rearward travel on the upper stretch of the chains, until they reach a point about midway of their return travel, at which point the tracks 58 are formed with an open space or gap 60 as shown in Fig. 2, thus dividing the tracks into a rear section and into a forward section. As the baskets leave the front ends of the rear sections of the tracks and enter these gaps, they being no longer supported by the tracks, will gravitate on the chains through 90° to an upright pendant position, and as they are carried forwardly by the chains the arms 18^b of the end frames of the baskets at one side, will engage the down curved rear end 61 of the forward sections of the tracks, and by such engagement the baskets will be rocked rearwardly on the chains through 90° and will be carried forward in this position, the baskets in their passage from the rear sections of the tracks to the forward sections being thus reversed in position by being turned through 180°. As a result of this reversal of the position of the baskets in their rearward and forward return travel, the coating material will be given a further opportunity to drain from and distribute itself evenly and uniformly throughout the surface of the articles, since any uneven distribution due to the articles being supported in one position in a portion of their travel, will be compensated for by a change in the position of the articles in the remaining portion of their travel.

In order to catch the coating material which may drain from the articles as they are carried rearwardly in the baskets on the upper stretches of the chains, I provide in the space between the chains of each conveyor element, an endless conveyor belt 62 (see Fig. 2), which belts pass at their front around drums 63 fixed to the shaft 34 before alluded to, and at their rear around drums 64 rotatable on the shaft 26 before alluded to. The upper stretches of the belts are in position to receive the coating material dripping from the articles held in the baskets, and the belts are driven in the direction of the full line arrow (Fig. 2) with their upper stretches moving forwardly, by means of a sprocket chain 65 driven from a sprocket wheel 66 on the shaft 39 and passing around a sprocket wheel 67 on the end

of shaft 34. By this means the coating material caught on the conveyor belts will be carried forwardly and delivered into the receptacle 45, the rear end of which is in a position relative to the belts to receive the material therefrom. 70

The forward ends of the tracks 58 are inclined upwardly as at 58^a (Fig. 3) and terminate a short distance from the idler sprockets 35, and as the chains 16 pull the baskets forwardly along these inclined ends of the tracks, due to the fact that the chains move in a path which intersects the tracks, the baskets will be tilted upwardly and forwardly on their chains as shown by dotted lines in Fig. 3, and will be drawn up the inclined ends of the tracks with the upper arms 18^a at one side of the end frames of the baskets resting thereon. As the basket is carried further along by the chains, it will be disengaged from the ends of the tracks, and in such disengaging action the lower arms 18^b will be dragged over the ends of the tracks and in doing so the basket will be tilted further forwardly and turned upside down and the article therein will fall from the basket by gravity and be received in the forward end of the tank 5, it being understood that the baskets on the chains will be thus turned bottom side up in succession, and will act to successively discharge the articles into the tank. 90

It will be noted from the foregoing description that in the different positions which the baskets assume relative to their carrying chains in the travel of the baskets from the nozzles 2 and 2^a to the point where the articles are discharged into the tank 3, the article is supported in the basket wholly by the pins 21 and 22. When the basket is in upright position as shown in Fig. 9 the article will be supported by both sets of lower pins 22; when the basket is drawn along on its side as on the upper stretch of the chains in Fig. 2, the article will be supported by both sets of pins 21 and 22 at one side, and when the basket is reversed in position as shown on the lower stretch of the chains in Fig. 2 to the right, the article will be supported by the pins 21 and 22 on the opposite side. I deem this manner of supporting the articles in the baskets to be of importance and advantage since the surface by which the article receives its support being of very limited area, practically confined to point supports, the supporting pins will not interfere with the flow of the coating material to all parts of the surface of the article, and the complete covering of said surface by the liquid coating material will be assured. 110

The conveyor 4 in the tank 3 is in the form of an endless belt which passes at its forward end around an idler drum 68 and at its rear end around a lower idler drum 69 and an upper idler drum 70, the belt being caused at its rear end to travel at an upward inclina- 120 125

tion in going around the upper idler 70, by means of an idler drum 71 beneath which the upper stretch of the belt travels near its rear end. The belt is provided with a series of 5 equally spaced transversely extending blades or cleats 72 between which the articles discharged into the tank from the baskets are received, and by which they are carried rearwardly in the tank through the treating solution, in this instance as before stated a neutral salt solution such as ammonium sulfate. The articles discharged from the baskets, fall against a deflecting shield 73 within the tank and extending transversely across the front 10 end of the same at a downward inclination and in such relation to the blades on the conveyor belt that the articles striking this shield will be deflected forwardly and in a position to be engaged by the blades. As the articles 15 on the belt are carried up the inclined rear portion of the belt, they are lifted in succession from the treating bath and delivered into the forward end of the tank 5 containing an acid treating solution such as sulfuric acid. 20

25 As the articles pass in succession from the end of the conveyor belt 4 they will be received on a downwardly inclined deflector plate 74 extending transversely across the interior of the tank 5 near its forward end, and by such plate 30 the articles will be deflected rearwardly and delivered to the endless conveyor 6 of the tank 5, which is similar in form and construction to the conveyor 4 and the belt of which passes at its forward end around a drum 75 35 and at its rear end around upper and lower drums 76 and 77 and beneath a guide drum 78. The articles on the conveyor 6 will as its belt travels upwardly around the upper guide drum 76, be lifted from the treating bath and 40 delivered into the forward end of the tank 7 containing the washing water, the articles as they are discharged from the conveyor 6 falling onto an inclined deflector plate 79 in the forward end of tank 7, and being deflected 45 by said plate to the conveyor 8 which is similar in construction to the conveyors 4 and 6, the belt of said conveyor 8 passing around a forward drum 80 and around upper and lower rear drums 81 and 82 and beneath a guide drum 83. The articles on the conveyor 8 will 50 be lifted from the rear end of the tank as the belt moves upwardly around the upper guide drum 81 and will be delivered in succession onto the forward end of the conveyor 9, consisting of an endless belt 84 traveling at its forward end around a drum 85 and rear end around a drum 86 which belt is provided with cleats 87 between which the articles will be carried. This belt carries the articles rearwardly and into the drier 11 by which the articles are finally dried and ready for use, the articles as they are carried rearwardly to the drier by the conveyor 9, passing beneath the discharge end of the nozzle 10. 60

65 In the form of the apparatus hereinbefore

described, the articles to be coated are placed by hand in the baskets as they pass upwardly in succession in an upright position on the forward sides of the front idler sprockets 23. I propose however to provide for the automatic feed of the articles to the upwardly moving baskets, which in the present instance may be effected by the feed mechanism illustrated in Figs. 14, 15, 16 and 17, where it will be seen that there is arranged in front of each 70 conveyor unit, a downwardly inclined runway or trough 88 on which the articles to be coated are placed so that they will roll down by gravity and be discharged from its lower end. From the runway the articles are released one at a time by an escapement mechanism 89 which delivers the same to a power operated feeding device 90 by which the articles are fed in succession to the baskets. 75

The escapement mechanism consists of a 80 detent member 91 pivoted between its ends on a horizontal axis as at 92 to a supporting frame 93 located between the discharge end of the runway and the sprocket wheels 23, the said detent member consisting of a front 85 block 94 and a rear block 95 connected together in spaced relations by parallel plates 96 fixed to the sides of the blocks, which latter are grooved in their upper sides to form guides for the articles. The forward 90 end of the detent member may thus be moved up on its pivotal axis from the position as shown in Fig. 14, in which position the front block 94 will be in alignment with the discharge end of the runway so that the article 95 from the runway will pass onto said block, to the position as shown in Fig. 15, in which position the block 94 will extend across the end of the runway and act as a stop for the next article. A fixed block 97 is supported 100 by the frame 93 and extends upwardly between the end blocks 94 and 95 and is grooved in its upper side to form a guideway for the articles, the said block 97 being in such position relative to the detent member that it will 105 act as a stop for the article supported by the block 94 as shown in Fig. 14 when the detent member is in its lowermost position, and when the detent member is moved upwardly 110 as shown in Fig. 15 the supported article will 115 pass onto the block 97 in which position of the parts the end block 95 will act as a stop for the article on the block 97, and will release 120 said article to permit it to pass to the feeding device 90 when the detent moves downwardly again. 125

The feeding device 90 is in the form of a rotary feed wheel having a hub 98 fixed to a horizontal shaft 99 journaled in bearings on the frame 93, from which hub a number of radial arms in the form of wire loops 100 extend and which arms as the wheel is rotated will sweep through a receptacle or pan 101 containing a supply of the coating material, which pan is supported by the frame 130

93 with its front end adjacent the end of block 95 in position to receive the articles rolling down said block, and having on its opposite end a downwardly extending lip 102 to direct the articles into the baskets. The feed wheel is rotated in a direction to cause the arms to sweep through the pan from front to rear, whereby the arms will engage the articles as they enter the pan in succession from the escapement mechanism and will deliver said articles successively over the lip 102 and into the baskets traveling upwardly on the forward sides of the wheels 23.

15 The detent member is moved up and down on its pivotal support by means of a toothed wheel 103 fixed to a horizontal shaft 104 mounted in bearings on the frame 93, the toothed edge of which wheel engages a roller 20 105 on the forward end of a horizontal lever 106 pivoted between its ends as at 107 to said frame, the rear end of the lever being pivoted to the lower end of a link 107^a whose upper end is pivoted to the rear end of the 25 block 95. The toothed wheel is rotated from the feeding device 90 by means of a sprocket chain 108 passing over a sprocket wheel 109 on the shaft 104 and over a sprocket wheel 110 on the shaft 99, the relative sizes of said 30 sprocket wheels being such as to cause the escapement mechanism and feed wheel to be so coordinated in their movements that the articles delivered in succession by the escapement mechanism will be engaged in succession by the arms of the feed wheel. The feed 35 wheel receives its motion from the shaft 24 by means of a sprocket chain 111 passing around a sprocket wheel 112 on the shaft 99 and around a sprocket wheel 113 on a shaft 40 114 mounted in bearings on the extension frame 15^a, the said shaft 114 having fixed to it a pinion 115 meshing with a pinion 116 on the shaft 24. The relative sizes of said 45 sprocket wheels and pinions is such that the movement of the feed wheel will be so coordinated with the movement of the baskets, that the latter will be positioned successively to receive the articles as they are successively delivered by the feed wheel from the rear 50 end of the pan 101.

The articles as they are moved by the feed wheel through the bath of coating material in the pan will receive on their surface a preliminary coating of said material, the purpose of which is to prevent the occurrence of bubbles or pin holes in the coating applied by the nozzles 2 and 2^a. It may happen that the coating material flowing downward from the nozzles 2 and 2^a will become aerated to some extent, and in flowing in this condition onto the article, bubbles may be formed resulting in pin holes in the coating. By applying a preliminary coating by means of the bath of the coating material in the pan 101, before 60 the main coating is applied by the nozzles

2 and 2^a, any liability of the formation of bubbles and pin holes in the coating will be avoided.

In order that the baskets may be freed of any adhering coating material, after the discharge of the articles into tank 3, I provide a tank 117 which extends transversely beneath the sprocket wheels 40 and which is supported by the frame extension 15^a. The tank is supplied with water, and is in such 70 position relative to the wheels 40, that the baskets will, in the travel of their carrying chains, be immersed in and carried through the water bath and thereby washed before they receive a new supply of articles.

Having thus described my invention, what I claim is:

1. The process of covering articles with a protective cellulosic coating, which consists in applying hydrated cellulose in liquid condition successively to different portions of the article to completely cover the same, treating the coated article successively with a solution of neutral salt and an acid solution, washing the treated article, and finally drying the same.

2. The process of covering articles with a protective cellulosic coating, which consists in applying hydrated cellulose in liquid form to the article to completely cover the same, supporting the coated article successively in relatively different positions to permit the material to distribute itself over the article and the surplus material to drain therefrom, and treating the cellulosic coating to coagulate the same.

3. In a coating apparatus, the combination of endless traveling chains, article holders carried by said chains, said holders being shiftable to different positions relative to the chains, nozzles for applying liquid coating material to the articles in the holders, said nozzles being arranged above the path of travel of the chains one behind the other, and means controlled by the travel of the chains for shifting the position of the holders on the chains relatively to the nozzles so that the two streams of coating material will be applied to different portions of the respective articles.

4. In a coating apparatus, the combination of endless traveling chains, article holders pivotally carried by the chains, means for applying coating material in liquid condition to the articles in the holders, a tank to contain a treating bath for the coated articles, means whereby the articles are automatically discharged from the holders into the forward end of the tank, means in the tank for carrying the articles rearwardly, a second tank to contain a bath for treating the articles from the first tank, and means for delivering the articles from the first tank into the second tank.

5. In a coating apparatus, the combination

of endless traveling chains, article holders carried by said chains and movable relatively thereto from a receiving position to a discharge position, means for applying liquid coating material to the articles in the holders, means for automatically moving the holders to discharge position, and a tank containing a bath of treating solution in position to receive the discharged articles.

- 10 6. In a coating apparatus, the combination of a series of traveling article holders, a receptacle to hold the coating material, and a feed wheel provided with arms movable through the coating material in the receptacle
15 to carry the articles to the article holders; whereby the articles delivered by the feed wheel to the holders will receive a preliminary coating of the coating material.

In testimony whereof, I have affixed my
20 signature hereto.

GEORGE W. BEADLE.
